UNITED STATES PATENT OFFICE.

NELSON E. FUNK, OF MONTCLAIR, NEW JERSEY.

PROCESS OF MAKING ENVELOPS.

1,135,786.

Specification of Letters Patent. Patented Apr. 13, 1915.

Application filed November 4, 1913. Serial No. 799,222.

To all whom it may concern:

Be it known that I, NELSON E. FUNK, a citizen of the United States, residing at Montclair, in the county of Essex and State 5 of New Jersey, have invented new and useful Improvements in Processes of Making Envelops; and I do hereby declare the following to be a full, clear, and exact description of the invention, such as will enable 10 others skilled in the art to which it appertains to make and use the same.

My invention consists in the novel features hereinafter described, reference being had to the accompanying drawings which 15 illustrate the manner in which my improved process is carried out, and said invention is fully disclosed in the following description and claims.

The object of my invention is to form 20 envelopes either with or without a window aperture, through which the address upon the inclosure may be seen, and in which case forms the address of the envelop, by a continuous process with the least possible waste 25 of material and in a rapid and efficient manner. The various operations upon the materials employed for the manufacture of the envelopes may be performed by hand or by the use of separate mechanical devices operated 30 by hand or by the use of machinery especially designed for carrying out my improved process. A machine of this type is illustrated and described in an application for Letters Patent of the United States filed 35 by me on or about November 4, 1913, Serial No. 799,221, but as before stated, my improved process is capable of being carried out by other and different means than those 40 therein shown. It is also to be understood that the materials employed in the manufacture 45 of the envelop, and which are advanced during the various steps of the process from one stage or operation to another, may be advanced continuously or intermittently as preferred.

In the accompanying drawings which illustrate my improved process and the manner in which the same is performed, Figure 1 represents the preferred form of my process, for the formation of envelopes having window apertures therein, covered with transparent fabric, the body of the envelop being formed from a continuous envelop blank strip preferably fed from a roll and 50 the transparent fabric being also fed as a 55 continuous strip from a roll. Fig. 2 is an

enlarged top plan view of portions of the envelop blank strip and transparent strip illustrating the various steps of my improved process to and including the formation of the complete envelop. Fig. 2^a is a front view of the completed envelop. Fig. 2^b is a plan view of one complete envelop as it would appear if it were opened out and laid upon a flat surface. Fig. 3 is a view similar to Fig. 2 showing a slightly modified form of blank strip and illustrating the steps of my improved process carried out for the manufacture of an envelop slightly differing from the envelop shown in Figs. 2, 2^a and 2^b. Fig. 3^a is a front view of the completed envelop shown in Fig. 3. Fig. 3^b is a plan view of the envelop shown in Fig. 3^a opened out flat. Fig. 4 is a view similar to Figs. 2 and 3 showing an envelop blank strip 75 similar to that shown in Fig. 2 in the different stages, illustrating the steps of my improved process, the window aperture and the transparent covering therefor being in this case omitted. Fig. 4^a is a front view of the 80 completed envelop illustrated in Fig. 4.

I will first describe my complete process in its preferred form for the manufacture 85 of an envelop having a window aperture and a covering of transparent material therefor, as illustrated in Figs. 1, 2, 2^a, and 2^b of the accompanying drawings.

The envelop itself is not of my invention, but in order that the various steps of my improved process may be more clearly understood, I will first describe the envelop which is to be produced thereby, special reference being had to Figs. 2^a and 2^b. The envelop comprises a rectangular front portion 10^b, a rectangular back portion 10^c, of 90 the same size as the front portion and integrally connected therewith, the line of fold being indicated at 1. The back portion 10^c has connected therewith a longitudinally 95 extending sealing flap 10^d, the line of fold 100 between said flap and the part 10^c being indicated at 2. The front of the envelop is provided at each end with an end sealing flap 10^e integral therewith, the lines of fold 105 being indicated at 3, 3. The form of this 105 envelop is such that it can be economically cut from a strip or blank having a width equal to the combined widths of the front, back, and sealing flap as will hereinafter more fully appear. In its preferred form, 110 the front of the envelop is provided with a window aperture 10^f which may be of any

desired shape and with a strip of transparent fabric 11, which extends from one end of the envelop blank to the other across the front portion and end sealing flaps thereof, 5 as shown, and is gummed or adhesively secured thereto, the said transparent strip being slightly wider than the window aperture 10^c. In the preferred form of the envelop, the transparent strip 11 is provided in those portions which lie upon and are secured to the end sealing flaps 10^a, with apertures 11^b. The envelop is completed by folding the back and front portions together at fold 1, folding the end flap portions 10^c 10 on the lines 3, 3, over upon the back 10^c together with the end portions of the transparent strip, and sealing the same upon the back of the envelop, whereby the end portions of the transparent strip are interlocked with the end sealing flaps and the said sealing flaps are sealed through the apertures 11^b upon the back 10^c, thus further locking the ends of the transparent strip and securing a better adhesion between 15 the end sealing flaps and the back of the envelop. The sealing flap 10 is folded on the line 2 over upon the front of the envelop, as best shown in Fig. 2^a. This sealing flap is provided with a gummed portion as indicated, and the front 10^b of the envelop is provided with a locking aperture 10^c in such position that the sealing flap will seal through said aperture upon the inclosure which carries the address to be viewed through 20 the window aperture, and hold the address carrying portion thereof against movement in the envelop, and also close to the inner surface of the front of the envelop, thus facilitating the reading of the address 25 through the transparent strip. The back of the envelop is also preferably provided with an aperture 10^d for the insertion of a knife or letter opener, or other instrument to facilitate the opening of the envelop after it 30 is sealed.

In carrying out my invention I prefer to form the body of the envelop as before stated from a continuous strip of paper or other suitable material which I term the 35 envelop blank strip, and which is indicated at 10 Figs. 1 and 2, a roll of this paper being indicated at 10^a. In carrying out my process continuously, this strip 10 is provided with the window apertures 10^c at suitable 40 intervals so that they occupy the proper position with respect to the individual envelops when severed, and the envelop blank strip is also provided with a band of gum indicated at 4 which extends longitudinally 45 of the blank adjacent to and between the window apertures and being of a width slightly greater than said apertures. I may first form the apertures and then coat the strip with the band 4 of gum, or I may apply the gum by means of a suitable recipro-

cating or rotary die roll, or by hand, leaving ungummed portions substantially corresponding to the size of the window apertures and thereafter cut out the ungummed portions.

The window apertures may be cut out by hand operated dies or otherwise, as preferred, and the envelop blank strip may be moved forward during the formation of the envelop either continuously or intermittently. I also provide the envelop blank strip with gum at those portions indicated at 5 in Figs. 1 and 2 which are to form the sealing flaps. I prefer to apply the gum at separated portions 5 instead of as a straight band as it facilitates cutting out the intermediate portions of the blank without fouling the cutting mechanism, which will be readily understood. The gum used for the sealing flap will be of a character usually employed for this purpose and I prefer to use a different kind of gum for the band 4, which is specially adapted to adhere to the transparent strip and secure it to the body of the envelop.

The transparent strip 11 is preferably drawn from a supply roll 11^a and is fed either by hand or by suitable mechanical means to and simultaneously applied to the gummed band 4 of the envelop blank strip so that the transparent paper is applied progressively from one end of the blank or blank strip to the other, and firmly sealed thereto over the window aperture or apertures thereof.

I prefer to provide the transparent strip with a looped portion 11^b to accommodate the intermittent feed of the envelop blank strip, and I also prefer to employ a suitable tension device, for example, a device capable of deflecting the paper strip out of a straight line, the preferred location of which is indicated at 32 in Fig. 1, for holding the transparent strip taut before it passes to and is placed in contact with the gummed portion of the envelop blank strip.

I may in some instances completely form the envelop blank in the shape shown in Fig. 2^b and apply the transparent continuous strip from one end of the same to the other and then sever the strip after it has been applied, or I may in some instances apply the continuous transparent strip to a plurality of envelop blanks of substantially the form shown in Fig. 2^b, the strip continuing from one blank to another and thereafter severing the transparent strip to separate said blanks, but I prefer in most instances to apply the strip continuously to a continuous envelop blank strip, as shown in Figs. 1 and 2, and to sever both strips simultaneously as hereinafter described, to separate the envelop blank strip into the individual envelops. I also prefer to perforate the transparent strip 11 as indicated at 11^b in Figs. 1 and 2,

at such portions thereof as will fall upon and be applied to the end flap portions of the envelop blank or envelop blank strip. The strip 11 may be perforated at the time immediately before its application to the envelop blank strip, or it may be previously perforated and rolled up into the roll 11^a as preferred. I prefer, however, to perforate it immediately before it is applied to the envelop blank strip. It is also to be understood that while I prefer to apply gum for the transparent strip to the envelop blank which has more body and is less liable to curl and become distorted, I may in some instances apply the gum to the transparent strip and then apply the gummed transparent strip to the envelop blank or envelop blank strip, this being within the scope of my invention.

The transparent strip having been applied to the envelop blank strip, the next step of my process consists in partially blanking the envelop, which is accomplished by cutting out transverse portions of the envelop blank strip as indicated at 6 and 6^a without entirely severing the strip. The cut-out portions 6 terminate at their inner extremity in a V-shaped notch 6^b which with the cut-out portions 6^a also V-shaped, define the ends 30 of adjacent end flaps of two adjoining blanks and the cut-out portions 6 at their outer extremity increase in width as indicated at 6^c, thereby defining the end portions of adjacent sealing flaps. I also provide the envelop blank strip with the perforations or apertures 10^e and 10^b before referred to at the proper points. I now apply to the transverse portions of the envelop blank strip in line with the cut-out portions 6 and 6^a and 40 which are to form the end flaps of adjoining envelopes, a coating of gum applied in any suitable manner, as indicated at 7 in Figs. 1 and 2, and it will be noted that this gum is applied to portions of the envelop blank strip, and portions of the transparent strip lying upon the same and through the apertures 11^b upon the portions of the envelop blank strip beneath. The envelop blank strip is then given a preliminary or 50 first fold, the semi-detached portion of the envelop blank strip forming the back and sealing flap of the envelop, being folded on the line 1 over upon the integral portion of the strip so that the gummed face of the sealing flap will face downwardly and the sealing flap will extend beyond the edge of the integral portion of the envelop blank strip as clearly shown in Figs. 1 and 2. I prefer to apply the gum to the sealing flap 60 portions of the envelop blank strip at such time that it will be dry when this fold just described is made, so that it will no longer be sticky. The individual envelopes are now separated from the envelop blank strip by severing the envelop blank strip and the

transparent strip transversely and centrally of the transversely gummed portions 7, as indicated at the right in Figs. 1 and 2, and the envelop is completed by folding over the end flaps, sealing them against the back of the envelop, and also folding and creasing the sealing flap of the envelop, as indicated in Figs. 2 and 2^a, the latter of which represents the front view of the finished envelop. It will be obvious that in carrying out my improved process continuously, the envelop blank strip remains intact up to the moment when it is severed through the center of the transverse gummed portions 7, immediately before the final folds of the end flaps and sealing flap are made, so that it can be fed forward continuously or intermittently either by hand or by suitable feed rollers, or other mechanical means and operated upon progressively, in the manner indicated in the drawings. In my companion application hereinbefore referred to, which shows and describes a machine for carrying out my improved process, one form of mechanism for advancing the envelop blank strip and the transparent strip intermittently is shown and described.

In Fig. 1 of the drawings, I have indicated certain mechanical instrumentalities which can be conveniently employed if desired in carrying out my improved process. For example, 53 represents a die roll having cutaway portions 53^a substantially corresponding to the size and shape of the window apertures which may be conveniently employed for applying the band of gum to the continuous envelop blank strip, leaving the ungummed portions to be subsequently cut out, as before described, and 54 represents a gumming die roll provided at its periphery 100 with die portions corresponding to the gummed portion of the sealing flap for applying the gum for that purpose to the appropriate portion of the envelop blank strip. I have also indicated in Fig. 1 certain instrumentalities which may be conveniently employed for advancing the envelop blank strip and withdrawing it from its roll. Thus 14 and 15 represent feed rollers for positively withdrawing the strip from the roll after 115 which it is preferably allowed to form a loop or slack portion 10^x; I prefer to employ a tension device (for example, a device which will deflect the paper out of a straight line and as indicated at 31) for applying a desired degree of tension or friction to the strip which then passes over an impression roll 36 beneath the gumming die rolls before described, after which the strip passes between the impelling rolls 80^b and 81^b, for example, which may be employed to advance the paper and simultaneously roll down the transparent strip; and 140^a and 141^a represent other impelling rollers co-acting with corresponding lower rollers indicated in dot- 125

ted lines and engaging the partially folded strip at different points transversely and longitudinally, each of said rollers 140^a and 141^a being provided with a notch 140^c and 141^c respectively so located as to bridge over the transversely gummed portions 7 while advancing the strip and positively controlling it up to the point where it is severed. It will thus be seen that when devices of this character are employed the envelop blank strip will be impelled or advanced by devices acting upon it at different points and moving it forward against the tension device the preferred location of which is indicated at 15 31 the resistance of which remains constant and the strip advancing devices are relieved from the drag of the paper roll. Such devices I prefer to employ in carrying out my process by mechanical means as shown in my 20 companion application, but as before stated, I do not limit myself to the use of these or any other mechanical devices as the entire process may be carried out by hand or by hand supplemented by the use of simple 25 hand tools, such as shears, or hand knife and paste brush, as will be readily understood.

In Figs. 3, 3^a, and 3^b I have shown a slight modification of my process which consists merely in transferring the sealing flap 30 from the back of the envelop to the front portion thereof so that when it is folded, it is folded over upon the back of the envelop instead of upon the front of the envelop. The process is exactly the same as that heretofore described with this single exception, and the parts of the envelop blank strip, the transparent strip, and the envelop itself have been lettered identically with the corresponding parts shown in Figs. 1 and 2, and 40 the sealing flap is lettered 10^{dx} in order to avoid confusion, as they are otherwise identical with the parts shown in these figures.

Figs. 4 and 4^a represent the application of my improved process for the manufacture of 45 an envelop not provided with a window aperture or the transparent strip covering the same, the envelop blank alone being acted upon in the manner heretofore described with reference to Figs. 1 and 2, except that 50 the application of a gummed band across the envelop, the perforation of window apertures, and the application of the transparent strip are dispensed with. As shown in these 55 figures the envelop blank strip is partially blanked by removing transversely disposed portions 6, and defining the end flaps, as indicated at 6^a, 6^b, and the sealing flap as indicated at 6^c, all exactly as heretofore described with reference to Figs. 1 and 2. The 60 envelop blank strip is also preferably provided with a perforation 10^b to enable the point of a knife, letter opener, paper cutter, or other tool to be inserted therein for facilitating the opening of the envelop. The 65 transverse portions 7 in line with the cut-out

portions are gummed as before described, the back portion of the envelop 10^c is folded over upon the integral portion of the envelop blank strip as before described, and the envelop blank strip is severed transversely of 70 the gummed portions 7 after which the end flaps 10^e are folded over and sealed upon the back 10^c, and the sealing flap 10^d is folded and creased, thus completing the envelop, which is exactly like the envelop shown in 75 Figs. 2^a and 2^b, except for the aperture and the transparent paper covering for same.

It will also be obvious that in making the envelop without the window aperture as shown in Figs. 4 and 4^a the sealing flap may 80 be formed either on the portion of the envelop blank strip forming the back of the envelop as shown, or upon the portion of the envelop forming the front, as shown at 10^{dx} in Fig. 3, without departing from my invention.

What I claim and desire to secure by Letters Patent is:—

1. The herein described process for the manufacture of envelopes, having a window aperture and a covering of transparent material therefor, which consists in supporting a blank provided with a window aperture, applying adhesive material to a portion of said blank of less width than said blank, and including the edges of said aperture and the portions of the blank which are to form the end sealing flaps of the envelop and applying a transparent strip of less width than said blank upon the gummed portions thereof, whereby when the end flaps of the envelop are folded and sealed, portions of the transparent strip will be interfolded therewith.

2. The herein described process for the manufacture of envelopes having a window aperture, and a covering of transparent material therefor, which consists in forming a blank with a window aperture in that portion which is to form the front body portion of the envelop, adhesively applying a portion of a continuous transparent strip of less width than the blank thereupon and over said window aperture, without severing said transparent strip, severing said transparent strip after the applied portion has been adhesively attached to the body portion of the envelop, and folding other portions of the blank over upon the portion having the transparent strip secured thereto.

3. The herein described process for the manufacture of envelopes having a window aperture and a covering of transparent material therefor, which consists in feeding an envelop blank provided with a window aperture, applying gum to a narrow portion of the envelop blank extending longitudinally thereof, around the edges of the window aperture and upon portions of the blank which are to form the end flaps of the

envelop, and feeding a transparent strip of less width than said blank and applying the same progressively to the gummed portions thereof longitudinally of the blank, 5 over the window opening and upon said end flap portions, whereby when the end flaps are folded, portions of the transparent strip will be folded therewith.

4. The herein described process for the manufacture of envelopes having a window aperture and a covering of transparent material therefor, which consists in feeding a continuous envelop blank strip, forming address viewing window apertures therein at intervals, adhesively applying a continuous strip of transparent material of less width than the blank strip to the blank strip progressively, over said window apertures, and severing said transparent strip, blank- 20 ing the envelop blank strip to define the body portions, end flaps, and sealing flap, and folding said body portions together severing the individual envelop blanks from the blank strip, and sealing the end flaps.

5. The herein described process for the manufacture of envelopes having a window aperture and a covering of transparent material therefor, which consists in feeding a plurality of contiguous envelop blanks 30 end to end, provided each with a window aperture disposed longitudinally with respect to the line of feed, applying gum to narrow portions of the envelop blanks successively adjacent to the edges of the window apertures and upon portions between the apertures of adjacent envelop blanks which are to form the end sealing flaps of the envelopes, applying a continuous transparent strip of less transverse width than 35 the envelop blank to the gummed portions of said envelop blanks whereby when the end flaps of the envelop are folded, portions of the transparent strip will be interfolded therewith, and severing said transparent strip between adjacent envelop blanks.

6. The herein described process for the manufacture of envelopes, having a window aperture, and a covering of transparent material therefor, which consists in supporting a blank provided with a window aperture, applying adhesive material to a portion of said blank of less width than said blank, and including the edges of said aperture and the portions of the blank which are to form the 50 end sealing flaps of the envelop, and applying a transparent strip of less width than said blank upon gummed portions thereof, and subsequently applying gum to the portions of said transparent strip lying upon the end flap forming portions of the envelop blank.

7. The herein described process for the manufacture of envelopes, having a window aperture, and a covering of transparent material therefor, which consists in supporting 55

a blank provided with a window aperture, applying adhesive material to a portion of said blank of less width than said blank, and including the edges of said aperture and the portions of the blank which are to form the end sealing flaps of the envelop, and applying a transparent strip of less width than said blank upon gummed portions thereof, and subsequently sealing the end flap forming portions and the portions of the transparent strip adhering thereto, upon other portions of the envelop blank.

8. The herein described process for the manufacture of envelopes, having a window aperture, and a covering of transparent material therefor, which consists in supporting a blank provided with a window aperture, applying adhesive material to a portion of said blank of less width than said blank, and including the edges of said aperture and the portions of the blank which are to form the end sealing flaps of the envelop, and applying a transparent strip of less width than said blank upon gummed portions thereof, and subsequently applying gum in lines extending transversely of the blank, upon said end flap forming portions and upon the portions of the transparent strip lying upon said end flap forming portions.

9. The herein described process for the manufacture of envelopes having a window aperture and a covering of transparent material therefor, which consists in feeding a plurality of contiguous envelop blanks end to end, provided each with a window aperture disposed longitudinally with respect to the line of feed, applying gum to narrow portions of the envelop blanks successively adjacent to the edges of the window apertures, and upon portions between the apertures of adjacent envelop blanks, which are to form the end sealing flaps of the envelopes, applying a continuous transparent strip of less transverse width than the envelop blank to the gummed portions of said envelop blanks, applying adhesive material to the portions of said transparent strip adhering to the said end flap forming portions, and severing said transparent strip between adjacent envelop blanks, whereby when the end flaps of the envelop blanks are folded, portions of the transparent strip will be interfolded therewith, and sealed upon other portions of the envelop.

10. The herein described process for the manufacture of envelopes having a window aperture and a covering of transparent material therefor, which consists in feeding a plurality of contiguous envelop blanks end to end, provided each with a window aperture disposed longitudinally with respect to the line of feed, applying gum to narrow portions of the envelop blanks successively adjacent to the edges of the window apertures, and upon portions between the aper-

tures of adjacent envelop blanks, which are to form the end sealing flaps of the envelopes applying a continuous transparent strip of less transverse width than the envelop blank 5 to the gummed portions of said envelop blanks, and severing said transparent strip between adjacent envelop blanks, and sealing the end flap forming portions of the envelop and the adhering portions of the 10 transparent strip over upon the other portions of the envelop blank.

11. The herein described process for the manufacture of envelopes having a window aperture and a covering of transparent material therefor, which consists in feeding a plurality of contiguous envelop blanks end to end, provided each with a window aperture disposed longitudinally with respect to the line of feed, applying gum to narrow 15 portions of the envelop blanks successively adjacent to the edges of the window apertures and upon portions between the apertures of adjacent envelop blanks, which are to form the end sealing flaps of the envelopes, 20 applying a continuous transparent strip of less transverse width than the envelop blank to the gummed portions of said envelop blanks, applying adhesive material in lines extending transversely of the envelop blank 25 upon the end flap forming portions, and the portions of the transparent strip adhering thereto, and severing said transparent strip 30 between adjacent blanks, whereby when the end flap forming portions are folded and 35 sealed, portions of the transparent strip will be interfolded therewith and sealed upon other portions of the envelop blank.

12. The herein described process for the manufacture of envelopes having a transparent window portion in one wall, which 40 consists in feeding a continuous envelop blank strip, providing said strip with transparent window portions at intervals therein, cutting out transverse portions of the envelop blank strip in line with portions between adjacent window portions, to form 45 semi-detached portions at one side of the blank strip of a size sufficient for one complete wall of the envelop, and defining end 50 flap portions of adjacent envelop blanks, without severing the strip, folding said semi-detached portions over upon the integral portions of the envelop blank strip, severing the individual envelop blanks centrally 55 through said defined end flap portions, and sealing the end flap portions at each end of the envelop over upon said semi-detached portions.

13. The herein described process for the manufacture of envelopes having a transparent window portion in one wall, which 60 consists in feeding a continuous envelop blank strip, providing said strip with transparent window portions at intervals therein, cutting out transverse portions of the en- 65

velop blank strip in line with portions between adjacent window portions to form semi-detached portions at one side of the blank strip of a size sufficient for one complete wall of the envelop, and defining end 70 flap portions of adjacent envelop blanks, without severing the strip, folding said semi-detached portions over upon the integral portions of the envelop blank strip, gumming the defined end flap portions, 75 severing the envelop blank strip centrally of said defined end flap portions, and sealing said gummed end flap portions at each end of the envelop over upon the semi-detached portions. 80

14. The herein described process for the manufacture of envelopes having a window aperture and a covering of transparent material therefor, which consists in feeding a continuous envelop blank strip provided at 85 intervals with window apertures, applying gum to said envelop blank strip around the edges of said apertures, applying a transparent fabric of less width than the envelop blank strip to said gummed portions, to 90 cover the window apertures, partially blanking the strip by cutting out transverse portions and forming semi-detached portions between said cut out portions at one side of the envelop blank strip, and defining the end 95 flap portions of adjacent envelop blanks, without severing said blank strip, folding the semi-detached portions over upon the integral portions of the envelop blank strip, severing the envelop blank strip substantially centrally through the defined adjacent 100 end portions, and folding and sealing the end flap portions at each end of the envelop blanks over upon the said semi-detached portions. 105

15. The herein described process for the manufacture of envelopes having a window aperture and a covering of transparent material therefor, which consists in feeding a continuous envelop blank strip provided 110 with window apertures, applying a transparent strip of less width than the envelop blank strip over said apertures, partially blanking the envelop blank strip without severing it, gumming certain portions of the 115 partially blanked strip, folding the partially blanked strip, severing the blank strip into individual envelop blanks, and folding and sealing portions of the same to complete the envelop. 120

16. The herein described process for the manufacture of envelopes having a window aperture and a covering of transparent material therefor, which consists in feeding an envelop blank strip provided with window 125 apertures, applying gum to said blank strip around and between said apertures, applying a transparent strip of less width than the envelop blank strip to the gummed portions of the blank strip, cutting away por- 130

tions of the blank strip to define individual envelop blanks, and folding, severing and sealing the individual envelop blanks.

17. The herein described process for the manufacture of envelopes having a window aperture and a covering of transparent material therefor, which consists in feeding a continuous envelop blank strip, forming window apertures therein at intervals extending longitudinally of the strip and located nearer one side of the strip than the other, applying gum to a narrow portion of the envelop blank strip around and between the window apertures therein, applying a strip of transparent material narrower than the envelop blank strip to the gummed portions thereof, cutting out portions of the envelop blank strip to partially blank the same without severing it, folding portions of the partially blanked strip upon other portions thereof without severing said strip, applying gum to portions of the partially blanked strip, severing said partially blanked strip into individual envelop blanks, and folding and sealing the last mentioned gummed portions.

18. The herein described process for the manufacture of envelopes having a window aperture and a covering of transparent material therefor, which consists in providing a continuous envelop blank strip with window apertures at intervals, adhesively applying a continuous transparent strip to the envelop blank strip progressively over the window apertures thereof, partially severing said strip and folding portions thereof upon the integral portions of the strip, gumming transverse portions of the envelop blank strip forming the end flaps, and the portions of said transparent strip adhesively connected therewith, severing the envelop blank strip through said transversely gummed portions, and folding the end flap portions and the portions of the transparent strip adhering thereto over upon the body of the envelop.

19. The herein described process for the manufacture of envelopes having a window aperture and a covering of transparent material therefor, which consists in providing a continuous envelop blank strip with window apertures at intervals, adhesively applying a continuous transparent strip to said blank strip over the successive apertures therein, removing transversely disposed portions of the said blank strip without severing the strip to form semi-detached portions between successive portions removed, gumming transverse portions of said blank strip and the portions of the transparent strip adhering thereto, folding the semi-detached portions of the blank strip over upon the integral portion of the blank strip, severing the envelop blank strip and transparent strip through the transversely

gummed portions of each severed envelop blank over upon the body of the envelop.

20. The herein described process for the manufacture of envelop having a window aperture and a covering of transparent material therefor, which consists in providing a continuous envelop blank strip with window apertures at intervals, adhesively applying a continuous transparent strip to the said envelop blank strip over the said apertures thereof, cutting out transversely disposed portions of the strip to form semi-detached portions between the cutout portions and to define the end flap portions and sealing flap portion of the envelop blank without severing said blank strip, applying gum to transversely disposed portions of the envelop blank strip and adhering portions of the transparent strip, in line with said cut-out portions, folding the said semi-detached portions of said blank strip over upon the integral portions of the blank strip, severing both of said strips through the said transversely gummed portions, folding the transversely gummed end portions of the severed envelop blanks upon the body of the envelop, and finally folding the sealing flap over upon the envelop body.

21. The herein described process for the manufacture of envelopes having a window aperture and a covering of transparent material therefor, which consists in providing a continuous envelop blank strip with window apertures at intervals, adhesively applying a continuous transparent strip to the envelop blank strip over said window apertures, providing said transparent strip with apertures in the portions thereof which lie upon the end flap portions of the envelop blank strip, cutting out transverse portions of the envelop blank strip to form semi-detached portions between said cut-out portions removed without severing said strip, applying adhesive to the transverse portions of the envelop blank strip and the perforated portions of the transparent strip lying thereon, folding the semi-detached portions of the envelop blank strip between said cut-out portion over upon the integral portions of the envelop blank strip, severing the envelop blank strip through said transversely gummed portions, and folding the transversely gummed end flap portions over upon the body of the envelop.

22. The herein described process for the manufacture of envelopes which consists in cutting out transversely disposed portions of a continuous envelop blank strip without completely severing said strip, to define the body portions, and the end flaps and sealing flap gumming transversely integral portions of the strip in line with the cut out portions, folding the semi-detached portions of said strip between successive cut out portions over upon the integral portions before com-

- pletely severing said strip, severing transversely the integral transversely gummed portions of said strip between said folded semi-detached portions which transversely 5 gummed portions form the end flaps of the envelop, and sealing the end flaps upon the body portions of the envelop.
23. The herein described process for the manufacture of envelopes which consists in 10 cutting out transversely disposed portions of a continuous envelop blank strip without completely severing said strip, to define the body portions and end flaps and sealing flaps, gumming transversely disposed integral portions of said strip, in line with the cut out portions, which form the end flaps, folding the semi-detached portions of the strip between successive cut out portions, over upon the integral portions between the 20 transversely gummed portions thereof, before severing the strip, severing the strip transversely substantially centrally of the transversely gummed portions, and folding the gummed end flaps over upon one of the 25 body portions of the envelop.
24. The herein described process for the manufacture of envelopes, which consists in cutting out transverse portions of a continuous envelop blank strip at intervals without 30 severing said strip to form semi-detached portions of greater width than the remaining portion of the blank, folding said semi-detached portions over upon the main blank so that the outer portions thereof will 35 project beyond the edge of the integral portions and form the sealing flap of the envelop, severing the envelop blank strip through the transverse portions in line with said cut out portions, folding and sealing the end 40 flap portions so formed over upon the body of the envelop, and folding the sealing flap portion over upon the body of the envelop.
25. The herein described process for the manufacture of envelopes, which consists in 45 cutting out transverse portions of a continuous blank strip at intervals, severing said strip to form semi-detached portions of greater width than the integral portions of the strip, applying gum to transverse por-

tions of the strip in line with said cut-out 50 portions, folding said semi-detached portions over upon the integral portions of the strip so that the outer end portions thereof will project beyond the edge of the integral portion of the strip to form the sealing flap, 55 severing the said strip centrally through the transverse gummed portions, folding and sealing the transverse gummed portions at each end of the severed envelop blank over upon the body of the envelop, and folding 60 said sealing flap longitudinally of the envelop upon the body of the same.

26. The herein described process for the manufacture of envelopes having a window aperture and a covering of transparent 65 material therefor, which consists in feeding a continuous envelop blank strip, forming address viewing window portions therein at intervals, adhesively applying a piece of transparent material of less width than the 70 said blank strip, upon the same and over a window aperture therein, blanking the blank strip to define the envelop body portions, end flaps, and sealing flap severing the individual envelop blanks from the blank 75 strip, and sealing the end flaps upon one of the body portions of the envelop.

27. The herein described process of making envelopes provided with window apertures, and a covering of transparent mate- 80 rial therefor, which consists in feeding a continuous blank strip provided with window apertures, adhesively applying a continuous strip of transparent material of less width than the said blank strip to the same 85 over the window apertures, and subsequently blanking the envelop blank strip, to define the body portions, end flaps, and sealing flap of an envelop, one of the body portions of the envelop blank containing said win- 90 dow aperture.

In testimony whereof I affix my signature, in the presence of two witnesses.

NELSON E. FUNK.
